UNITED STATES PATENT OFFICE.

CHARLES D. YOUNG, OF ALTOONA, PENNSYLVANIA.

SUPERHEATER.

1,224,990.

Specification of Letters Patent.

Patented May 8, 1917.

Application filed October 31, 1913. Serial No. 788,390.

To all whom it may concern:

Be it known that I, CHARLES D. YOUNG, a citizen of the United States, residing at Altoona, in the county of Blair and State of Pennsylvania, have invented certain new and useful Improvements in Superheaters, of which the following is a specification.

The invention relates to superheaters for use upon locomotive and traction and other engines, although certain features are particularly adapted for use in traction engines, and the device is hereinafter described and illustrated as applied to a traction engine. The principal objects of the invention; are the provision of a cheap, compact arrangement wherein the individual tubes may be easily removed and replaced without disturbing other tubes, and wherein the ends of the tubes secured in the headers are readily accessible without the use of a plurality of handholes; and the provision of an improved superheater tube arrangement whereby a maximum superheating effect is secured with a minimum length of tube.

25 One embodiment of the invention is illustrated in the accompanying drawings, wherein—

Figure 1 is a longitudinal section through a boiler equipped with my improved superheater, on the line I—I of Fig. 3, the superheater drum also being shown in section; Fig. 2 is a section through one of the fire tubes of the boiler, taken at right angles to the section of Fig. 1, and Fig. 3 is a transverse section on an enlarged scale, taken on the line III—III of Fig. 1.

Referring to Fig. 1 of the drawings, 1 is the boiler of a traction engine provided with the relatively large fire tubes or flues 40 2 extending from the firebox of the boiler to the smoke box 3 and carrying the superheater tubes; 4 is the steam dome from which steam is supplied to the superheater by means of the dry pipe 5; 6 is the outlet pipe leading from one of the superheater headers to the cylinders; and 7 is the exhaust nozzle for securing draft in the smoke box.

Secured to the flue sheet of the boiler is a cylindrical drum 8 provided with a vertical wall 9 intermediate the ends of the drum, such wall serving to divide the drum into the two headers 10 and 11. The dividing wall or partition 9 is provided with 55 a relatively large opening which is normally closed by means of the cover 12 held remov-

ably in position by means of the stud 13 and brace 14, although any desired means may be employed for this purpose. The outer chamber 11 is also provided in its end wall with an opening normally closed by means of the cover 15, also held in place by means of the usual stud and brace as illustrated. The outlet pipe 6 leading from the header 11 is provided with a valve 16 which may be located in any desired position with respect to the boiler.

A plurality of superheater tubes 17, 18, 19, 20, 21, 22, 23, and 24 are employed, each of which tubes has one of its ends expanded into the wall of the chamber 10, and its other end expanded into the wall of the chamber 11. As indicated in Figs. 1 and 3, the two ends of any particular tube lie one behind the other, and from Fig. 3 it will be seen that no tube lies in front of another tube, so that any individual tube can be removed without the necessity of removing another tube. This is of course of advantage in case it becomes necessary to replace one or more tubes while the other tubes are in position. This result is best accomplished by having the upper ends of the tubes bent radially with respect to the drum, and making each tube lie either to the inside or the outside of the adjacent tube.

As indicated in Figs. 1 and 2, each superheater tube comprises four lengths, 25, 26, 27, and 28, the lengths 25 and 28 extending substantially throughout the length of the fire tubes, while the lengths 26 and 27 are approximately only half as long. This arrangement is of advantage in that the major portion of each tube is located at the end of the fire tube adjacent the fire box where the temperature of the heated gases is highest. I have found that the heating effect is better with this arrangement than in one where the lengths 26 and 27 are made the same as that of the lengths 25 and 28, since the lengths of tubing in the extremity of the fire tube, adjacent the smoke box tend to lose heat, due to the lower temperature of the gases at such portions of the fire tubes. Furthermore the friction is decreased by using the relatively short lengths 26 and 27, since the lengths of superheater tube through which the steam must be passed is correspondingly decreased. The cost of the tubing is also obviously less with the less length than is the case where the four

lengths extending substantially the entire length of the fire tube is used. Another advantage incident to the construction is due to the fact that retardation of the gases passing through the flue is less where the short lengths 26 and 27 are employed, than where such lengths extend throughout the full length of the fire tubes.

It will be understood that the advantages 10 as above set forth may be achieved even where the length of the tube parts 26 and 27 is increased or decreased over the proportions shown, and that my invention is not limited to the precise construction 15 shown, which merely serves to illustrate the principle involved.

The employment of the relatively large 20 openings for the cover plates 12 and 15 is desirable, in that the ends of the tubes can be expanded or cut out by workmen operating through these openings, thus avoiding the necessity of employing a plurality of hand holes or covers in the walls of the header chamber, opposite the tube ends. 25 Various other advantages incident to the construction of the drum and tubes, and the arrangement of the tubes, will be readily apparent to those skilled in the art.

What I claim is:

- 30 1. In combination with a boiler having a fire box and smoke box and fire tubes extending through the boiler from the fire box to the smoke box, a pair of superheater headers, an inlet for supplying saturated steam from the boiler to one header, an outlet 35 from the other header, and a plurality of superheater tubes each having one end connected to one header and the other end

connected to the other header, such tubes each leading into a fire tube at the front 40 end thereof, extending in a straight length from its point of entrance into the tube to a point adjacent the rear end of the fire tube, recurring and extending to the front a relatively short distance as compared with the 45 length of the fire tube, then recurring and extending to a point adjacent the rear end of the fire tube, and finally recurring again and extending in a straight length out through the front end of the fire tube. 50

2. In combination with a boiler having a fire box and smoke box and fire tubes extending through the boiler from the fire box to the smoke box, a pair of superheater headers, an inlet for supplying saturated steam from the boiler to one header, an outlet from the other header, and a plurality of superheater tubes each having one end connected to one header and the other end connected to the other header, such 60 superheater tubes each comprising four lengths only lying in a fire tube with two lengths extending substantially the entire 65 length of the fire tube and the other two lengths extending only a relatively short distance as compared with the first two lengths, and such shorter lengths lying adjacent the fire box end of the fire tubes.

In testimony whereof I have hereunto signed my name in the presence of the two 70 subscribed witnesses.

CHARLES D. YOUNG.
